UNITED STATES PATENT OFFICE.

PHILIP MUELLER AND ANTON C. SCHUERMANN, OF DECATUR, ILLINOIS, ASSIGNORS
TO ADOLPH MUELLER, TRUSTEE, OF DECATUR, ILLINOIS.

DOUBLE-HEAD DRINKING FOUNTAIN.

Application filed October 29, 1919. Serial No. 334,168.

To all whom it may concern:

Be it known that we, PHILIP MUELLER and ANTON C. SCHUERMANN, citizens of the United States, residing at Decatur, in the county of Macon and State of Illinois, have invented new and useful Improvements in Double-Head Drinking Fountains, of which the following is a specification.

The present invention relates to sanitary drinking fountains of the pedestal type, and has for its object to provide a fountain of this character in which provision is made for a plurality of drinking streams or bubbles; with an independent supply and independent supply controlling means for each bubble; and a waste pipe common to all of said drinking heads or bubbles. Furthermore, it has for its object to so dispose various parts as to give a compact, simple and easily assembled structure, provision being made for ready access to and repair of the parts without the necessity of taking down the entire structure.

In the drawings herewith is illustrated one embodiment of the invention, and in said drawings:—

Figure 1 is a sectional view of a fountain made in accordance with the invention.

Figure 2 is an enlarged vertical section of the basin and the supply and waste pipe connections.

Figure 3 is a plan view of the base plate of the fountain with the supply valves and their operating parts, supply pipes, and waste pipes in section; the pedestal being shown in section and in position on the base plate; the bowl and bubbler-heads being in dotted lines.

Figure 4 is a plan view on the line 4—4 of Figure 1 looking downwardly.

Referring to the drawings by numbers, like numbers indicating like parts in the several views, 10 denotes a base plate which is substantially cruciform, and has the arms 11 through the ends of which lag screws 12 pass to secure the fountain to the floor or foundation.

The arms 13 are provided with lag screws 12 similar to those just mentioned, and the arms 13 have, furthermore, the pedestal-locating pins 14 designed to engage suitable locating apertures in the base of the pedestal, as shown in Figure 1. The base plate has a centrally disposed apertured boss 15

which receives the end of the waste pipe 55 section 16, the said waste pipe section being secured therein in any suitable manner, as by the screws 17 and projecting below the base-plate, where it is connected in any suitable manner with a waste or sewer pipe 60 (not shown). Arranged adjacent the central boss 15 are two supply pipe bosses 18 through which the supply pipe nipples 19 pass, these nipples being secured in any suitable manner as by the screws 20, and extending 65 below the base plate for connection with any suitable supply.

To each of the supply pipe sections 19 are secured supply valves 21, and said supply valves may be of any suitable type, the 70 type shown having a spring inlet valve, the stem 22 of which is provided with fork-engaging sleeve to connect with the forked end of a pedal lever 23, which is pivoted at 24 to a projection on the cock body, and the 75 operating arm or foot piece 25 of which extends outwardly through a slot 26 in the pedestal base and into the pedal crescent or housing 27 with which the pedestal is provided, the lever 23 preferably moving in 80 guide lugs 28 formed on the base plate 10. With this arrangement, it will be observed that upon depression of a pedal lever 23, a valve stem and spring valve will, through the fork and sleeve connection shown, be 85 actuated to open the valve and permit water to flow from the lower supply section 19 through a valve to the upper supply pipe section 29. Preferably, a stop and regulator 30 of any suitable type will be provided, by means of which the flow through the supply valve may be controlled, and, if desired, may be completely cut off.

The supply pipe sections 29 rise within the pedestal from the supply valves and adjacent the waste pipe, to a point near the top of the pedestal where they are provided each with a bell-mouthed nipple 31, which nipple has secured thereto in a proper manner, as by a wiped joint, a flexible pipe section 32, shown in Figure 2, which flexible pipe section may be of lead if desired. The flexible pipe sections 32, when the pipe is set up and the pedestal is placed in position, may be 100 conveniently bent or flexed to bring their ends to the wall of the pedestal, their ends being provided with suitable connecting nipples, as the bell-mouthed nipples 33, which

- nipples 33, through openings 34 in the wall of the pedestal, may be coupled to the tail pieces 35 of the bubbler elbows 36, which connect with the lower ends of the bubbler 5 nipples 37, which extend upwardly through the basin and are provided with any suitable bubbler heads 38, the bubbler heads, as shown in Figs. 2 and 3, being located on opposite sides of the bowl near the ends 10 thereof.

It will be seen that with this arrangement a close assemblage of the waste pipe, supply pipes, and valves is provided within the pedestal, and that such waste and supply 15 pipes may be rigidly secured to the base plate; and, by means of the flexible connections from the supply pipes to the tail pieces of the bubbler heads, the fittings may be set up and the entire apparatus installed without 20 the necessity of manipulating any nuts or threaded connections within the pedestal. In assembling, the base-plate will be set in proper position to meet the roughed-in waste and supply pipes, the waste pipe and 25 two supply pipe nipples with their supply valve will be installed, after which the pedestal will be dropped over the assembled fittings and located in proper position by means of the pedestal-locating pins.

30 The pedestal will then be secured or clamped to the base by means of a clamping plate 39 (see Figs. 1, 2, and 4) which plate has a sliding fit over the waste pipe 16, and the arms of which rest upon lugs 40 formed 35 on the inner wall of the pedestal, (see Figs. 1 and 4). Said clamping plate 39 and the pedestal are forced downwardly by screws 41 mounted in the flange of a cap nut 42, which cap nut is threaded on or otherwise 40 suitably secured to the top of the waste pipe 16 and has an inner annular gasket 43 to form a packing between it and the bowl waste pipe. Prior to affixing the bowl to the pedestal, the flexible pipe sections 32 45 will be bent to the position indicated so as to bring the nipples 33 in proper relation to the openings 34 in the wall of the pedestal and the tail pieces 35 of the bubbler heads may be secured to the bell-mouthed nipples 50 33. The bowl 44 may be then dropped into place, with its bowl-waste pipe 45, which is tapered for a sliding entrance, projecting 55 into the top of the waste pipe and properly sealed by the gasket 43 in the cap nut 42, this bowl waste pipe being secured to the 60 under side of the bowl pipe by screws 46, which serve also to fasten the strainer 47 in place. The tail-pieces 35 will then be coupled by any suitable coupling means to the elbows 36 of the bubbler heads.

The bowl 44 rests upon the top of the pedestal, as shown in Fig. 1, and may be secured thereto by screws 48 which pass through lugs 49 on the pedestal and engage 65 in suitable lugs or projections on the rim of

the bowl, so that by simply removing the screws 48 and uncoupling the elbow connection the basin or bowl may be lifted from the pedestal. By releasing the clamping plate 39 and swinging it clear of the lugs 42, the pedestal may then be lifted clear and access had to the fittings within the pedestal. 70

In order that the valves 21 may be attended to for regulation and repair, without the necessity of taking down the fountain, it will be seen that, first they are located, as best shown in Figs. 1 and 3, in close relation to each other at one side of the waste pipe in the generally V-shaped arrangement shown, and that, second, the pedestal is provided with a handhole 50 at a point which gives ready access to the valves when the handhole cover 51 is removed. 75

Such changes as are within the range of mechanical skill may, of course, be made 80 without departing from the spirit of the invention, and we do not, therefore, limit ourselves to the structural details herein disclosed. 85

We claim:—

1. The combination in a drinking fountain of a pedestal, a basin on the pedestal, a waste pipe for receiving waste from the basin and arranged within the pedestal, a plurality of supply pipes within the pedestal, a plurality of bubbler heads supported by the basin and each having a substantially horizontal tail piece beneath the bottom of the basin and extending into the pedestal, and tubular members of ductile metal connecting the ends of said bubbler head tail pieces with the supply pipes within the pedestal. 90

2. The combination in a drinking fountain of a pedestal, a waste pipe extending vertically within the pedestal, a basin on the pedestal having a waste outlet connected to the upper end of the waste pipe, a plurality of supply pipes within the pedestal, a plurality of bubbler heads each connected to a conduit that has one member extending through the bottom of the basin and another extending beneath the basin toward the waste outlet, and flexible pipes connecting the last said members with the supply pipes within the pedestal. 105

3. The combination, in a drinking fountain, of a base, a pedestal on said base, a single basin on said pedestal, a rigidly held waste-pipe traversing said pedestal to receive waste from said basin, rigidly held supply-pipes traversing said pedestal and extending to a point near the top thereof, separate bubbler heads in said basin having supply connections extending through the bottom thereof outside of said pedestal, and connections from said rigid supply pipes to said bubbler heads passing through openings in the walls of said pedestal, and having flexible sections to facilitate assembling. 110

4. The combination, in a drinking fountain, of a base, a pedestal mounted on said base, a single basin on said pedestal, a waste-pipe traversing said pedestal to receive waste from said basin, rigid supply pipes traversing said pedestal and extending to a point near the top thereof, separate bubbler heads in said basin having supply connections extending through the bottom thereof outside of said pedestal, elbow connections for said bubbler heads beneath said basin, and flexible connections between said elbow connections and said supply pipes.
5. The combination, in a drinking fountain, of a base a pedestal mounted on said base, a single basin on said pedestal, a rigid waste-pipe traversing said pedestal to receive waste from said basin, rigid supply pipes traversing said pedestal to a point near the top thereof, flexible sections secured to the upper ends of said rigid supply pipes, separate bubbler heads in said basin outside of said pedestal, bubbler elbows beneath said basin, and tail-pieces secured to said flexible sections and detachably coupled to said elbows.
6. The combination, in a drinking fountain, of a pedestal, a plurality of supply pipes spaced from one another in said pedestal, a plurality of supply valves for said pipes the ends of which converge to bring them in close proximity to one another, and a handhole in the wall of said pedestal opposite the converging ends of said supply valves.
7. The combination, in a drinking fountain, of a base, a pedestal on said base, a waste-pipe mounted in said base and traversing said pedestal centrally, a plurality of spaced apart supply pipes mounted in said base between said waste-pipe and the pedestal wall, supply valves for said supply pipes converged upon one another with their ends adjacent the pedestal wall, and a handhole in said wall opposite said valves.
8. The combination, in a drinking fountain, of a base, a pedestal on said base, a waste pipe mounted on said base and traversing said pedestal centrally, a plurality of supply-pipes mounted in said base between said waste-pipe and the pedestal wall, a plurality of supply valves for said pipes the ends of which converge outwardly from said pipes toward the wall of said pedestal, a handhole in said wall opposite said valves, and valve-operating levers extending outwardly through the opposite wall of said pedestal.
9. The combination, in a drinking fountain, of a base, a pedestal mounted on said base and having a handhole in its wall on one side and a plurality of pedal-receiving crescents in the wall on its opposite side, a waste-pipe mounted in said base and traversing said pedestal centrally, a plurality of supply pipes mounted in said base in proximity to one another and between said waste-pipe and the handhole wall of said pedestal, a plurality of supply-valves the ends of which converge toward said handhole, and valve-operating pedal levers extending from the opposite diverging ends of said valves into the crescents of said pedestal.
10. The combination in a drinking fountain of a pedestal, a waste pipe extending vertically within the pedestal, a basin on the pedestal having an outlet communicating with the waste pipe, two bubbler heads within the basin, supply pipes within the pedestal and connected to the bubbler heads, a valve controlling the flow of water through each supply pipe, said valves being located within the pedestal and closely adjacent each other at one side of the waste pipe, two diverging levers extending outward through the pedestal and each connected with one of said valves, and a removable closure for an opening in the pedestal adjacent said valves and through which access may be had thereto.
11. The combination in a drinking fountain of a pedestal, a waste pipe extending vertically within the pedestal, a basin on the pedestal having an outlet communicating with the waste pipe, two bubbler heads in the basin, water supply pipes within the pedestal and connected to the bubbler heads, a valve controlling the flow of water through each supply pipe, said valves being within the lower portion of the pedestal and closely adjacent each other at one side of the waste pipe, two diverging foot levers connected to said valves and extending outward through openings in the pedestal, and a removable closure for an opening in the pedestal through which access may be had to both valves.
- In testimony whereof we have hereunto set our hands.
- PHILIP MUELLER.
ANTON C. SCHUECKMANN.
